UNITED STATES PATENT OFFICE.

ALTHEOD J. HOULE, OF MANCHESTER, NEW HAMPSHIRE.

BAG CONVEYING AND SUPPORTING TRUCK.

SPECIFICATION forming part of Letters Patent No. 729,866, dated June 2, 1903.

Application filed February 13, 1903. Serial No. 143,254. (No model.)

To all whom it may concern:

Be it known that I, ALTHEOD J. HOULE, a citizen of the United States, residing in Manchester, in the county of Hillsboro and State of New Hampshire, have invented a new and useful Improvement in Bag Conveying and Supporting Trucks, of which the following is a specification.

This invention relates to that class of trucks 10 adapted for transporting or conveying bags of merchandise, and particularly to the class in which the bag is held in a vertical position in order that it may be filled at the source of supply and the truck with the filled bag then 15 trundled away to a point where the bag may be closed or transported or disposed of in any desired manner.

The nature of the invention is fully described below and illustrated in the accompanying drawings, in which—

Figure 1 is a plan view of my improved device, a portion being represented as broken out in order to illustrate one of the top pins. Fig. 2 is an elevation of the same.

Similar letters of reference indicate corresponding parts.

a represents a level platform, preferably rectangular in shape and somewhat longer than it is wide, and provided on its under 30 side near the corners with suitable casters *b*. The upper surface near the corners is provided with vertical posts *e*, preferably metallic and made of flat or other shaped material, said posts being secured to the platform by bolts *c*, which extend through the feet *d*.

The two posts at each end are connected and made rigid by suitable horizontal braces *f*, which are bolted at *g* to said posts. The rigidity of the posts is further secured by 40 means of the diagonal braces *h*, which are bolted at their opposite ends at *k* to the said posts *e* and the platform *a*. These posts are preferably set with their edges toward the center of the platform. Bolted at *l* to the

45 upper portion of one of the faces of each post is a vertical guard, whose main portion *m* sets out at some distance from the post, said guard being preferably of flat metal and of substantially the same width as the post. A number 50 of pins *n*, arranged in a vertical row, extend horizontally from each post at substantially right angles thereto between said guard *m*

and the post, said pins in each row being also at substantially right angles with a horizontal line drawn from the post to the center of the 55 platform, and hence at right angles with the line of direction of the pull of the bag. Suspended from one of said pins in each row is a swinging supporting-bar *s*, provided with a series of holes *p* for the longitudinal adjustment thereof. The said bar has on its lower end a hook *t*, turned upward toward its under side. *w* represents a bag for containing grain, coal, fruit, or other merchandise adapted to be shipped in bags. 60

In operation the bag is placed centrally with relation to the platform at such a height that its lower end just touches the platform, and the bars *s* catch into the four corners of the bag by means of the hooks *t*, said bars being suspended by slipping each on one of the pins *n* by means of one of the holes *p*, such pins and holes being selected as will allow the bag to be extended centrally for its full length in the position illustrated. The truck 75 may then be trundled to the place where the bag is to be filled and afterward drawn to the place from which it is to be removed, sold, stored, or transported. The bars *s* are placed with their hooked ends *t* extending downward 80 instead of upward in order that the bag may be more readily attached and for the purpose of lessening the danger of injury to the persons who are handling them and the bags.

Having thus fully described my invention, 85 what I claim, and desire to secure by Letters Patent, is—

1. A bag conveying and supporting truck, consisting of a substantially level platform provided with suitable casters; upright posts secured at their lower ends to the platform and extending up therefrom at suitable distances apart; substantially vertical rows of, pins secured to and extending substantially horizontally from said posts at substantially 90 right angles with horizontal lines extending from the posts to the center of the platform; and bars provided with means whereby they may be caught over said pins, and formed at their lower ends with means whereby they may 95 be attached to the upper edge of a bag, said parts being combined and arranged substantially as and for the purpose set forth.

2. A bag conveying and supporting truck,

consisting of a substantially level platform provided with suitable casters; upright posts secured at their lower ends to the platform and extending up therefrom at suitable distances apart; substantially vertical rows of pins secured to and extending substantially horizontally from said posts at substantially right angles with horizontal lines extending from the posts to the center of the platform; bars provided with a row of perforations whereby they may be caught over said pins, and formed at their lower ends with hooks turned upward toward the under sides of said

bars whereby they may be attached to the upper edge of a bag; and guards secured to the posts and extending over and along said rows of pins, said parts being combined and arranged substantially as and for the purpose set forth.

In testimony whereof I have signed my name to this specification in the presence of two subscribing witnesses.

ALTHEOD J. HOULE.
